United States Patent

Des. 237,387
Patented Oct. 28, 1975

237,387

END FRAME FOR A SERVOMOTOR

William E. Monroe, Oak Park, Mich., assignor to
The Bendix Corporation, South Bend, Ind.

Filed Jan. 16, 1973, Ser. No. 324,021

Term of patent 14 years

Int. Cl. D13—01

U.S. Cl. D26—5 A

FIG. 4

FIG. 1

FIG. 3

FIG. 2

FIG. 1 is a front perspective view of an end frame for a servomotor showing my new design;

FIG. 2 is an end elevation view thereof;

FIG. 3 is a front elevation view thereof; and

FIG. 4 is a cross-sectional view thereof taken along the line 4—4 in FIG. 2.

I claim:

The ornamental design for an end frame for a servomotor, as shown.
